(Cl. D80—11)

FIG. 1

FIG. 2

FIG. 1 is a front perspective view taken from the top and one side of a display case for razor sets and the like showing my new design, the opposite side being a mirror image of the side shown and the rear being inset and substantially plain as indicated in FIG. 2; and

FIG. 2 is a cross-sectional view thereof taken on line 2—2 of FIG. 1.

The dominant features of my design reside in the portions shown in full lines, it being understood that the brick-like pattern, fragmentarily shown in broken lines on the sloping front panel, is continuous across the plane surfaces of said panel, except for the surface of the indicia bearing element.

I claim:

The ornamental design for a display case for razor sets and the like, substantially as shown and described.
